SLEEVE PRESS

Rollin E. Campbell and Harry D. Forse, Anderson,
Ind.; said Campbell assignor to said Forse

Application November 12, 1949, Serial No. 126,864

2 Claims. (Cl. 223—73)

1

This invention relates to a sleeve press for the pressing or ironing of shirt sleeves. Since each shirt includes two sleeves the press is of dual sleeve accommodating type. However, since sleeve length and/or girth may vary for reasons well understood, the sleeves even of dissimilar length can be simultaneously ironed.

Since for laundry use successive shirts may have different lengths and girths, the press of the present invention is arranged to accommodate substantially all shirts as hit and miss supplied thereto.

The chief object of the present invention is to provide a sleeve press wherein the shirt sleeve is mounted upon a tapering buck telescopically received within and pressed or ironed by a frusto-conical hollow heated head, said buck being of expansible type.

Another chief object of the present invention is to prevent undue buck expansion until it is head confined so as to prevent buck rupture, tearing or jamming.

A further chief object of the present invention is to provide a sleeve press that is manually initiatable and thereafter is automatically controlled until the ironed sleeves are exposed for removal from the press.

The chief feature of the present invention resides in providing a sleeve press of such construction and so controlled that the foregoing several objectives are accomplished.

Other objects and features of the invention will be set forth more fully hereinafter.

The full nature of the invention will be understood from the accompanying drawings and the following description and claims:

In the drawings—

Fig. 1 is a front elevation of a dual sleeve press embodying the invention, the bucks being shown in sleeve receiving and removing position, one of the bucks and its associated head being shown in longitudinal section.

Fig. 2 is a side elevation thereof with the bucks and heads in pressing position.

Fig. 3 is a top plan view thereof.

Fig. 4 is a schematic piping diagram of the pneumatic system embodied in the invention.

In Figs. 1 and 2 of the drawings, 10 indicates a base from which rises a post or standard 11. Disposed rearwardly thereof is a substantial parallel cylinder 12 mounting therein, see Fig. 4, a piston 13 carried by piston rod 14 which projects upwardly.

The upper end thereof, see Fig. 2, has arm 15 connected thereto and the arm is of offset character and has its lower end connected to the

2

upper end of tubular guide 17. This guide mounts transversely disposed cross head 18 provided at the ends with elongated guides 19.

In each is slidably mounted rod 20 which is elongated and at the lower end mounts link 21 and above the cross head mounts collar 22. Concentric with the rod and bearing at opposite ends upon the cross head and collar is the spring 23.

When rod carried buck 24 cannot rise further, incident to head 25 limiting such travel, the cross head can rise to the extreme limit of its travel, the spring 23 compressing as shown in Fig. 2 at this time, compare positions A, B and C.

The buck comprises a frusto-conical elongated shell 26, see Fig. 1, of light sheet rubber clamped at the top as at 27 and at the bottom as at 28. A single conduit 29 serves as an inlet and outlet for air supply and release, respectively.

Each head 25 is frusto-conical in form and slightly longer and larger than the buck. It is jacketed as at 30 so that steam can be applied thereto for heating the inner surface, which heated surface irons the sleeve when mounted upon the buck.

The cuff clamp ears 32 are attached to hemispherical shells 33. The shells 33 are pivotally mounted on piston rod 34. Piston structure 34a is slidably mounted in cylinder 35 within the buck. The cylinder 35 is rigid with buck 24. Tension spring 36 tends to pull the clamp ears 32 together and thus dispose them in clamping relation upon the buck upper end.

When a shirt sleeve is applied to the buck 24 as shown in Fig. 1 left hand side, the cuff clamp ears 32 are applied to the unbuttoned cuff on the buck, as shown at the right hand side, same figure. Now when the buck nests in the head and further upward travel of the buck is prevented, continued upward cross head movement causes adjustment screw 31a to engage valve 31, thereby introducing air into cylinder 35. At this time, of course, the open cuff is trapped upon the buck by the head. Thus no cuff clamp mark is left upon the ironed cuff.

It appears proper to here point out that when the two bucks are in lowered position same are deflated. The sleeves of a shirt are applied over the upper ends of the buck and drawn down thereon and smoothed down. The cuffs are then clamped by ears 32. Then the bucks are elevated into the heads. Note the bucks can accommodate various sleeve lengths and girths. During such elevation the bucks are but slightly inflated and as long as not substantially fully registered within the heads the bucks cannot be highly inflated. Note

the slopes of the ears, bucks and heads are substantially alike.

There is provided in the buck supply and release line 29 a relief valve structure that when the buck is not nested prevents buck pressure accumulation greater than the low pressure desired for sleeve stretching etc., and which upon buck nesting in the head permits high pressure accumulation in the buck. Herein the link 21 supports floating bar 37 mounting valve body 40 supporting ball 41, see Fig. 4, nesting by gravity upon seat 42 to seal off vent 43 in free communication with lines 29.

To prevent high pressure in the buck before entering the head a second safety relief valve is provided. It comprises valve 45 having seat 46 controlled by ball 47. Line 48 thereto connects to supply line 29 to which branch lines 49 and low pressure relief line 43 are connected. Bracket 50 pivotally supports at 59a arm 51 having loop 52 therein. Disposed therein is a rod 53 having a head 54 at the upper end. Rod 53 is slidably mounted in guide 55. Gravity, normally acting upon the rod 53 through arm 51, holds valve 47 closed after the cross head has sufficiently elevated to lift rod 53 off of base 10, the weight of rod 53 being sufficient to hold ball 47 on seat 46 against high pressure inflation.

Reference will now be had more particularly to the lower portions of Figs. 1 and 2. The base 10 includes spaced forwardly projecting guard portions 57. Disposed in the space thus defined is the oppositely tiltable foot operable lever 58 carried by arm 59 mounted on rocker shaft 60.

A standard 61 rising from base 10 adjustably mounts one end of spring 62, the other end being connected to cam member 63 pivoted at 64 upon standard 65. Standard 65 supports U-shaped stop 66 with so-called lower stop 67 at the top and so-called upper stop 68 at the bottom. A bumper roll 69 is carried by angle arm 70 tiltable with lever or treadle 58.

Tiltable with said lever or treadle is the cam roller 71 and the same rides the cam face 72 which is V-shaped and forms the cam member 63. Thus the roller is disposed over-center in one position or the other relative to said face 72.

A cylinder 73 is pivoted at 74 upon another extension of the bumper carrying arm 70. In this cylinder is a piston 75, see Fig. 4, carried by rod 76 pivoted at 77 upon standard 61. This cylinder and piston structure is for timing the duration of pressing or ironing.

The structure described requires manual actuation of control 58 to start the cycle after the sleeves have been applied to the bucks. This control structure effects automatically the return of all parts to starting position. In the event it is desired to manually effect return or to effect return before completion of the cycle the treadle lever 58 is reversely actuated.

Reference will again be had to Fig. 4. Herein 78 indicates a pressure supply line that maintains a constant pressure supply, say 60 p. s. i. It enters combination inlet and exhaust unit 79 having an inlet valve with stem 81 and an exhaust valve with stem 82. The release is through exhaust 80 or muffler.

A line 82' serves as a common holding, exhaust and supply line. A branch 83 contains a low pressure regulator 84. Another branch 85 contains a check valve 86. Line 49 aforesaid connects to both. High pressure in line 82' seals check 86. Line 82' beyond the regulator take-off includes choke 87 and this choked line 88 connects to lifting cylinder 13. The latter has a

shock absorber and a regulated bleeder relief 89.

Branching from line 82' is line 90 that includes regulating or timer valve 91. The same discharges by line 92 to cylinder 13 having piston 75 therein. This cylinder has ports 93 therein. The operation briefly is as follows:

When the treadle is depressed the high pressure valve is opened at stem 81 and high pressure air is supplied through Venturi type choke 87 to the power cylinder. Low pressure air is also supplied to line 29 and the bucks are partially inflated and so held until the bucks are nested in the heads.

At this time the low pressure relief valve 40 is allowed to close and the safety valve 45 held shut. During this time high pressure air has been restrictively supplied to the timer device, 73-75 until ports 93 are uncovered which releases the automatic control to operate exhaust valve 82 to vent completely cylinders 13 and 12 and the bucks.

Pressing pressure in the bucks 24 creates a downward thrust in opposition to the upward thrust of cylinder 12. Proportionate rise and fall of pressures between the bucks 24 and the cylinder 12 must be maintained to prevent shifting of bucks while nested. This is accomplished by means of Venturi choke 87.

When all parts are returned to starting position automatically or manually, the inlet valve is again opened through stem 81 and the treadle as previously described.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a sleeve press having a tubular frusto-conical head member and a coaxial frusto-conical buck member, the two members having relative axial movement for telescopic association and disassociation, one of said members having flexible inflatable walls to provide an inflatable member and the other of said members having a heated surface, said surface and walls, when the members are nested, confronting each other for ironing a shirt sleeve therebetween, a support movable axially with respect to one of said members, yielding means supporting the other of said members on said support in axial alignment with the first mentioned of said members, means for moving said support, and means for moving said yieldably supported member a predetermined distance axially of said members to effect nesting of the same.

2. A sleeve press as defined by claim 1 wherein means is provided to inflate the inflatable member, and control means regulating the said inflation means to effect low pressure inflation prior to and during movement of the members toward one another and high pressure inflation when said members have reached complete nested association.
